This invention relates to reservoirs for the storage of liquefied gases at low temperatures, i.e., temperatures below -20° C .

The storage of liquefied gases in underground caverns has already been proposed and is in wide-spread use when the gases are stored under pressure at ambient temperature. However, the storage of liquefied gases at low temperatures, i.e. below -20° C . at substantially atmospheric pressure is a more difficult operation because of the low temperature effects on the earth formations surrounding the cavern and the shaft extending from the cavern to the surface of the earth. It is obviously ideal if earth formations, which are completely impervious to liquids and which will withstand the low temperatures without cracking, are available but this is very rarely the case. Certain earth formations, such as limestone, shales and granite and rock-salt are substantially impermeable to liquids and, if they contain cracks, these cracks can be sealed before the reservoir is put into use and so produce a perfectly impermeable natural cavern. However, when filling such a cavern with very cold liquids, there is a tendency for fissures and cracks to open up in the rock due to differential contraction of the materials making up the rock formation. When such fissures and cracks open up in the side walls or base of a cavern they are not normally serious because they do not result in any substantial spalling of the rock, and the fissures and cracks themselves are normally sealed by freezing of the ground water that enters them. However, the formation of such fissures and cracks in the roof of a rock cavern can lead to serious and unpredictable results. Unless the cavern roof is supported, these fissures and cracks can result in serious spalling of rock from the roof, a process which can go on until there is a complete subsidence of the upper earth formations into the cavern. It is true that this spalling can be prevented by suitable supporting structures but, in caverns of very substantial dimensions, such supporting structures are very expensive to build and maintain.

It has now been found that, if, in accordance with the present invention, steps are taken to maintain the roof of the cavern at a temperature above -20° C ., the danger of spalling from the roof is substantially eliminated. This can be done in any suitable way which will supply heat from an external source to maintain the roof temperature above -20° C .

However, a preferred form of the present invention provides a reservoir for the storage of liquefied gases at temperatures below -20° C . comprising an underground cavern in a rock formation, a shaft extending from said cavern to the surface of the earth, a thermally insulated false roof extending over the cavern below the rock roof of the cavern and heating means for maintaining a temperature of above -20° C . in the space between said false roof and said rock roof.

A further difficulty in connection with underground caverns for storing liquefied gases at low temperatures, arises in connection with the shaft which extends from the cavern to the surface of the earth in which generally all necessary piping arrangements will lead down into the cavern. In order to keep ground water from flowing

2

into the shaft, it is generally necessary to line the shaft at least down from the surface until a liquid impervious ground layer is met. While such a lining works quite efficiently when the liquefied gases are stored at ambient temperatures, difficulties arise when these liquefied gases are stored at very low temperatures. Since the shaft normally forms part of the vapor space above the cavern reservoir, it will be subjected to these low temperatures and, owing to differential expansion and contraction between the shaft lining and the surrounding earth formations, gaps will open up which will permit leakage of gas from the reservoir.

The present invention also meets this difficulty since the heating means used for maintaining a substantially atmospheric temperature in the space between the false roof and the rock roof of the cavern may, at the same time, be used for maintaining such a temperature throughout the length of the shaft.

The present invention is particularly suitable for the storage of the following gases, stored at their boiling point at about atmospheric pressure, the temperature of which boiling point is given after each of the materials listed:

		$^{\circ}\text{C}$.
25	Methane	—161
	Ethylene	—104
	Ethane	—89
	Propylene	—48
	Propane	—42
30	Ammonia	—33
	Oxygen	—183
	Nitrogen	—196
	Hydrogen	—253
	Helium	—269

The underground cavern used in this invention may be either a naturally occurring one or may be excavated from living rock. Any local permeabilities in the rock can be sealed off by concrete or other suitable sealing compounds or, if the flow of ground water into the cavern is not a great quantity, one can rely on the cold product to be stored in the reservoir to freeze the water in local permeabilities and so automatically seal the cavern. A lined cavern will not generally be necessary unless the product to be stored therein has to be subjected to rigorous exclusion of contaminants, for example liquid hydrogen and liquid oxygen. In such cases a cheap lining of metal or a suitable plastic may be used. This lining need have no structural strength for its sole purpose is to prevent contamination of the stored products.

The shaft extending from the cavern to the surface of the earth is sealed at the top by a metal head through which pass the various pipes necessary for the operation of the storage reservoir, such as the charging line, discharge line and a vapor relief line for the gases boiling off from the stored product. It is, of course, essential to prevent the ingress of ground water into the shaft and this can be done, either by lining the shaft down to an impervious ground layer and sealing the lining into that layer or, alternatively, one can rely on maintaining a temperature of not below -20° C . but low enough to freeze the ground water and so seal off the shaft. Even in this latter case, however, a certain amount of lining will be necessary near the surface of the earth so that the suitable head can be put on the shaft.

The thermally insulated false roof extending over the cavern below the rock roof of the cavern is sealed into the rock wall by suitable means and can be supported by hangers from the rock roof. The thermal insulation may be hung below the false roof or may rest on the top of it. Generally, the roof will be made of sheet metal capable of standing up to the low temperatures

involved without embrittlement, such as stainless steel or aluminum sheet. If necessary, it can be provided with suitable expansion means, such as corrugations, in order that it can be subjected to a wide temperature range without permanent deformation.

The heating means for maintaining a temperature of above -20° C . in the space between the false roof and the rock roof and also, where desired, throughout the length of the shaft is conveniently a flow of comparatively warm gas of the same type as is to be stored in liquefied condition in the reservoir. By using the same gas, a number of advantages arise. Firstly, small leakages through the false roof do not become important if the nature of the gas on both sides of the false roof is the same. Secondly, the natural boil-off of the liquefied gas from the stored product in the reservoir can be used as a source of the warm gas. Thirdly, when the product stored in the reservoir is a combustible gas, such as a liquefied hydrocarbon or liquefied hydrogen, the use of the same gas above the false roof minimizes the danger of the formation of explosive mixtures.

The flow of warm gas in the space between the false roof and the rock roof, and where desired the shaft, may operate in a closed system of pipes or in free flow. Generally, the latter system is to be preferred since it ensures maximum heat transfer and also that the spaces are swept continuously by the gas, and the leakage of contaminated gases, such as air, into the spaces is avoided. Moreover, when using free flow, it is possible to control the pressure above the false roof so that it is always slightly higher than the pressure below the false roof, thus ensuring that any flow of gas across the false roof is a flow of warm gas into the reservoir rather than one of cold gas out of the reservoir, which might have adverse effects on the rock roof and the shaft. Of course, it is not necessary that gas flow be used as a heating means. Suitable liquid flow, such as warm water, flowing through suitable heat exchanger pipes can be employed. Also, where there is no danger of the formation of explosive mixtures, such as in the storage of liquefied oxygen, nitrogen and liquefied helium, ambient air can be blown through the space between the false roof and the rock roof and through the shaft to keep these spaces warm.

The invention will now be described in more detail with reference to the accompanying drawings, in which FIGURES I, II and III represent cross sections through typical reservoirs constructed in accordance with this invention, FIGURE I representing a reservoir involving the use of free gas flow as the heating means; FIGURE II involving the use of a closed gas flow cycle for said heating; and FIGURE III showing direct heating of the cavern roof.

Referring to FIGURES I and II, 1 is the ground level and 2 represents the level at which the sub-strata of rock are found. The ground between 1 and 2 is water permeable. The rock below level 2 is impermeable to liquids except in local fissures and cracks, which can readily be sealed off.

A cavern 3 exists in the solid rock and is connected to the earth's surface by a shaft 4. The cavern has been made liquid-tight by sealing off all local cracks by suitable concrete grouting. The upper part of the shaft 4 is lined by a metal liner 5, which extends down into the rock formation and is sealed into the rock at 6. The shaft is covered by a detachable head 7.

For filling the reservoir a charging line 8 passes through the head to the foot of the reservoir and a discharging line 9 passes from the submerged electric motor pump 10 up through the shaft and out of the shaft head. A vapor discharge line 11 also passes down the shaft and stops short of the highest level to which it is intended to fill the reservoir with liquid. A plate metal roof 12 covers the reservoir above the highest intended liquid level and below the rock roof of the reservoir 13. This

false roof 12 is suitably sealed into the rock at its perimeter as at 14 and may be provided with corrugations 15 to allow it to expand and contract without any permanent deformation. This roof can be supported from the rock roof 13 by suitable hangers 14a. The false roof 12 carries a suitable thermal insulating 16. This layer may be formed of any appropriate thermal insulating material, such as fibre glass, rock wool, balsa wood, perlite and foamed plastic, such as foamed polyurethane or foamed polyvinyl chloride. The charging line 8, discharging line 9 and vapor relief line 11 all pass through the said roof, the last line terminating just below the roof.

In accordance with this invention, the space between the false roof and the rock roof 13 is kept at a temperature above -20° C . by suitable heating means. Referring to FIGURE I, this heating means comprises a gas blower 17, a line 19, which line passes through the head of the shaft and down to the space between the false roof 12 and the rock roof 13. Before entering the shaft, the gas in line 19 can be heated, if necessary, in heater 18 to a suitable temperature for maintaining the desired temperature above -20° C . in the space between the false roof 12 and the rock roof 13, and the shaft 4. Heater 18 may operate on a cheap source of heat, such as ambient air, or river water or waste gases.

The line 19, at its lower end, connects with a distribution pipe 20 provided with suitable holes 21 for distributing the warm gas throughout the space to be maintained above -20° C . The gas flowing through this space exits through the head of the shaft by line 22 and hence returns to blower 17. To make up for any gas lost in this circulating system, gas may be directed from the vapor relief pipe 11 carrying vapor from the liquefied gas reservoir via branch line 23 and control valve 24.

Referring to FIGURE II, the heating system comprises the blower 17, line 19 and heater 18, as in FIGURE I, but line 19 in this case is extended into an arrangement of the heat exchange pipes distributed around the space to be heated, shown diagrammatically at 25, 26, and 27. After the warm gas has circulated through this heat exchange system, it exits through the head of the shaft via line 28 and so returns to the blower 17. Any losses are made up from the vapor relief line 11 via branch line 23 and valve 24, as in FIGURE I.

The pipes 8, 9 and 11 may be thermally insulated above the false roof to prevent cooling of the space above the false roof by the cold fluids passing through them.

Normally, the temperature in the space between the false roof and the rock roof and in the shaft will be maintained at substantially ambient temperature, i.e. between 0° C . and 20° C . These spaces will not normally be kept at temperatures below 0° C . unless it is necessary, owing to the absence of a shaft lining to freeze the ground water surrounding the shaft. In these cases, the temperature can go down to -20° C . but it is not wise to take the temperature any further than this since, otherwise, rock spalling may occur.

The arrangements shown in the figures are particularly suitable for the storage of liquefied natural gas and liquefied petroleum gases, but may also be used for any of the other gases mentioned at the commencement of this specification.

It will be apparent that the embodiments shown are only exemplary and that various modifications can be made in construction and arrangement within the scope of the invention as defined in the appended claims, e.g., the cavern roof may be maintained at the desired temperature or temperature range, as by embedding the heating pipes in the rock roof or very close to it, without using the thermally insulated false roof. FIGURE III shows such an arrangement in which the lines 19 and 28 of FIGURE II are connected to line 29, which are set directly against or very close to the roof, and may have projections 30 imbedded in the roof for more efficient transfer of heat.

I claim:

1. A reservoir for the storage of liquefied gases at temperatures below -20° C. comprising an underground cavern in a rock formation, a shaft extending from said cavern to the surface of the earth, a thermally insulated false roof extending over the cavern before the rock roof of the cavern and heating means supplied through said shaft for maintaining a temperature of above -20° C. in the space between said false roof and said rock roof.

2. A reservoir as claimed in claim 1 in which the heating means is also used for maintaining a temperature of above -20° C. throughout the length of the shaft.

3. A reservoir as claimed in claim 2 wherein the temperature in the space between the false roof and the rock roof is maintained at between 0° C. and 20° C.

4. A reservoir as claimed in claim 1 in which the shaft is lined at least down from the surface until a liquid impervious ground layer is met.

5. A reservoir as claimed in claim 1 in which the heating means comprises a free flow of warm gas.

6. A reservoir as claimed in claim 1 in which the heating means comprises a flow of warm gas through a closed gas circulation system.

7. A reservoir as claimed in claim 5 in which the gas is the same as the gas stored in liquefied form in the reservoir.

8. A reservoir as claimed in claim 7 in which make up for the circulating warm gas is provided from a vapor relief line from the reservoir.

9. A reservoir as claimed in claim 7 wherein the pressure above the false roof is maintained slightly higher than the pressure below the false roof.

10. A reservoir for the storage of liquefied gases at temperatures below -20° C. comprising an underground cavern in a rock formation, the roof of said cavern being formed by a part of the rock formation and being subject to spalling at the low temperature of the stored liquefied gases, a shaft extending from said cavern to the surface of the earth, heating means for maintaining the temperature

of the rock roof of the cavern at above -20° C., and means extending through said shaft for supplying said heating means with heat.

5 11. A reservoir as claimed in claim 10 in which the heating means include means for conducting a fluid heating medium down through the shaft into heat exchange relation with the cavern roof.

10 12. A reservoir as claimed in claim 1, said false roof comprising a metal plate roof suspended from the rock roof of the cavern by hangers, a layer of insulation supported on said plate roof, said heating means being between the insulation and the rock roof, filling and discharge pipes for stored liquid extending from the surface of the earth through said shaft and through said false roof, 15 means for circulating heat exchange fluid through said heating means and means at the surface for heating said fluid.

13. A reservoir as claimed in claim 12, said fluid being the same material as the liquefied gas which is stored, but 20 in gaseous form, a vent pipe extending from the vapor space immediately beneath the false roof to the surface, and a valved connection between said vent pipe and said heating means for supplying said heating means with gas from said vent pipe.
